OF D 5.641

UNITED STATES PATENT OFFICE.

ARTHUR M. KING OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 5,641, dated March 12, 1872.

To all whom it may concern:

Be it known that I, ARTHUR MAZEPPA KING, of Kidderminster, county of Worcester, England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates to a new design of the two main figures, A B, and of the ground C between them. The figure A represents a square within a lozenge-shaped outline, from

which eight narrow-pointed arms project. The figure B is a square with a V-shaped notch in the middle of each side.

I claim as my invention—

1. The design of the figure A, as shown.
2. The design of the figure B, as shown.
3. The design of the ground-work C, as shown.
4. The design for a carpet, consisting of the figures A, B, and ground C, as shown.

ARTHUR MAZEPPA KING.
